L. CHRISTMAS

THROTTLE ADJUSTING DEVICE AND SAFETY LOCK

Filed Feb. 23, 1922

UNITED STATES PATENT OFFICE.

LEE CHRISTMAS, OF GUATEMALA, GUATEMALA.

THROTTLE-ADJUSTING DEVICE AND SAFETY LOCK.

Application filed February 23, 1922. Serial No. 538,602.

To all whom it may concern:

Be it known that I, LEE CHRISTMAS, a citizen of the United States, residing at Guatemala city, Guatemala, have invented new and useful Improvements in Throttle-Adjusting Devices and Safety Locks, of which the following is a specification.

This invention has reference to an adjusting device and safety lock for the throttle levers of steam locomotives.

An important object of the invention is to provide means whereby, when the throttle is closed, the throttle lever becomes automatically locked and cannot be moved except by the engineer or other operative.

As an additional object, the invention contemplates the provision of a safety throttle-lever with an adjustable quadrant permitting minute lever adjustments to be obtained, besides affording means for maintaining the lever in any position in which previously set.

With these and other objects in view, which will become apparent as the description proceeds, the invention resides in the construction, combination and arrangement of parts, hereinafter more fully described and claimed, and illustrated in the accompanying drawings, in which like or bracters of reference indicate like parts throughout the several figures, of which:

Fig. 1 is a side view of a throttle-lever embodying the invention;

Fig. 2, a top view thereof, and

Fig. 3, an end view of the quadrant shown detached from the lever.

In describing the invention in detail, 10 indicates the quadrant to which is fulcrumed, as at 11, a throttle lever 12. This quadrant comprises a normally fixed body portion A and a movable end portion B; the latter being notched, as at 13, to provide quadrant teeth. A latch 14, similarly notched for engagement with the quadrant teeth, is mounted adjacent lever 12 for longitudinal adjustment and has a stem 15 slidable in a guide bearing 16. This latch is pressed against the quadrant to hold the lever in position by a spring 17 coiled about the guide stem as shown.

When the lever is positioned as in Figure 1, the throttle is intended to be closed, thereby cutting off the steam from the cylinders of the locomotive. It frequently happens, however, due either to the carelessness of the last one handling the locomotive in not

properly closing the throttle, or to a leaky throttle, that there may be such an accumulation of steam as to overbalance the throttle lever, especially if the teeth of the quadrant 60 be worn, and to release the engine, the running away of which is usually attendant with great loss of life and damage to property.

To prevent such an occurrence, lever 12 is 65 equipped with an automatic safety lock including a pin 18 at one end of a flat strip 19 which has its other end bent over a movable wedge block 20 and hinged to the lever at 21. Block 20 is connected to latch 14 70 from the opposite side of the lever by a bolt 22 which works back and forth in lever slot 23 and extends beyond strip 19 to support coil spring 24. Strip 19 is pressed inwardly by the spring which tends to force pin 18 75 through an opening in the lever so that it will engage in notch 25 of the quadrant when the throttle is closed. When so engaged, movement of the lever in a forward or throttle-opening direction is prohibited. 80 This pin-lock is automatic in operation and is engaged or released by movement of pivoted hand clasp 26 and latch lever 27. When latch lever is shifted to unseat latch 14, block 20 moves toward the hinged end of 85 strip 19, moving the latter outwardly to dislodge pin 18 and releasing the throttle. When the lever is shifted rearwardly to close the throttle and the hand clasp is released, strip 19 moves inwardly under pressure of 90 spring 24 as the block recedes and pin 18 reengages notch 25.

Should the teeth on quadrant 10 and latch 14 strike on end and not seat when the lever is set to give just the quantity of steam that the engineer wishes, notched part B of the quadrant may be adjusted sufficiently to seat the teeth, thereby rendering it unnecessary for the engineer to hold the lever in place, as at present, or to adjust it one notch more or less. This adjustment is effected by means of a screw bolt 28 turning in a nut 29 which is attached to quadrant part B. Lugs 30 on one side of the quadrant provide suitable bearings for the bolt which is also equipped with a hand wheel 31 for obtaining minute adjustments.

By rotating the bolt to the right or left, the notched end B of the quadrant is adjustable crosswise of quadrant body A in either direction. Hence, when the lever is in any set position, the quadrant may be

readily adjusted to engage and maintain the lever in the position in which set and when it is required to increase or diminish the steam supply only a trifle and without unlatching the lever, the latter can be adjusted bodily by merely rotating the bolt a distance of one or more threads or a fraction thereof as desired.

In practice, I have found that the form of my invention illustrated in the accompanying drawings and referred to in the above description, as the preferred embodiment, is the most efficient and practical; yet realizing that conditions concurrent with the adoption of my device will necessarily vary, I desire to emphasize that various minor changes as to form of construction, proportion and arrangement of parts may be resorted to without departing from or sacrificing any of the principles of this invention.

Having thus described my invention, and without enumerating variations and equivalents, what I desire protected by Letters Patent is as set forth in the following claims.

1. The combination with a locomotive throttle lever, a rack, a safety device coacting with the rack and comprising a stationary element having an opening or notch therein and a member carried by the lever adapted to automatically engage in said opening or notch when the lever is in throttle closing position.
2. The combination with a throttle lever; of a throttle quadrant embodying body and face portions, a catch carried by the lever for engagement with the teeth of the quadrant, and a spring pressed locking member carried by the lever adapted to automatically engage in a hole or notch formed in the quadrant when the lever is in throttle closing position, whereby inadvertent movement of the lever from such position will be prevented even though the rack and catch may not be properly engaged.
3. The combination with a throttle lever,

of a support to which the lever is pivoted, a rack having a movable face portion carried by the support, a catch carried by the lever engageable with the rack to hold the lever in adjusted position, a safety lock comprising a spring pressed projection carried by the lever adapted to automatically engage in a hole or notch in the support when the lever is in throttle closing position, and a single controlling member connected with said catch and locking projection to provide for the retraction thereof when it is desired to adjust the lever.

4. The combination of an adjustable lever, a catch carried by the lever, a rack comprising body and face portions, means carried by the body portion co-acting with means carried by the face portion to effect their relative adjustment to permit proper engagement of the catch with the face portion in any adjustment of the lever.

5. The combination of an adjustable lever, a catch carried by the lever, a rack comprising body and face portions, screw means carried by the body portion for engagement with means carried by the face portion to effect transverse movement of the face portion to permit proper adjustment of the catch with the face portion in any adjustment of the lever.

6. The combination of an adjustable lever, a catch carried by the lever, a rack comprising body and face portions, the end of the body portion being grooved and the end of the face portion presenting a rib or tongue for slid able engagement with the groove, and means carried by the body portion for engagement with means carried by the face portion to effect their relative adjustment to permit proper engagement of the catch with the face portion in any adjustment of the lever.

LEE CHRISTMAS.
